(57) **CLAIM**

The ornamental design for a package for e-kit with pouch,
as shown and described.

DESCRIPTION

FIG. 1 is a front view of a fully assembled package for e-kit
with pouch showing our new design;

FIG. 2 is a rear view thereof;

FIG. 3 is a right-side view thereof;

FIG. 4 is a left-side view thereof;

FIG. 5 is a top view thereof;

FIG. 6 is a bottom view thereof; and,

FIG. 7 is a front/right-side perspective view thereof.

(Continued)

The dashed broken lines in the drawings represent environmental subject matter that form no part of the claimed design.

1 Claim, 5 Drawing Sheets
